UNITED STATES PATENT OFFICE

CARL LAWRENCE MATTISON, OF ROCKFORD, ILLINOIS, ASSIGNOR TO MATTISON MACHINE WORKS, OF ROCKFORD, ILLINOIS, A CORPORATION OF ILLINOIS

SANDING DRUM

Application filed January 4, 1929. Serial No. 330,206.

This invention relates generally to sanding drums and in particular to rotary sanding drums embodying mounting, clamping and tensioning means for the sheets operatively associated therewith.

Generally a dominating object of the invention is to provide a sanding drum which may be easily and simply constructed and assembled to obtain a permanent, substantially 10 perfect, balance.

In connection with the foregoing object, a further object resides in the provision of sheet mounting clamping and tensioning structures incorporated in the drum which are separable 15 from the drum for easy assembly or replacement and which may be supplied as individual units.

Another object of the invention is to provide structures for operating upon the working 20 sheets in the form of a series of units each of which may be supplied for installation in a drum in a previously balanced and centered condition whereby the original balance of the drum will not be impaired.

Still another object of the invention is to provide a construction which facilitates the replacement of paper and padding by providing a new and improved paper clamping and tensioning means, as well as a simple 25 means for taking up slack in the padding.

Other objects and advantages will become apparent in the following description and from the accompanying drawing in which:

Figure 1 is a longitudinal cross section partially in elevation of a sanding drum embodying the construction by which the features of the invention are attained.

Fig. 2 is a transverse section along the line 2—2 of Fig. 1.

Fig. 3 is a transverse section taken substantially on the line 3—3 of Fig. 1 illustrating one of the clamping structures.

Fig. 4 is a similar transverse section taken on the line 4—4 of Fig. 1 to illustrate one of the tensioning structures.

Fig. 5 is an enlarged fragmentary detail of the padding adjusting means.

While the invention is susceptible of various modifications and alternative constructions, I have shown in the drawing and will

herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

In prior constructions, of the type to which this invention is pertinent, it has been customary to place a layer of padding such as felt between the drum and the sheet of abrasive paper. It has been found in practice that the continued action of the rotating drum on the work causes the layer of felt padding to stretch and loosen circumferentially of the drum. In addition, the abrasive sheet also stretches similarly and further looseness thereof is caused by the decrease in thickness of the stretched felt thereby producing considerable slack in the abrasive surface.

In attaining the objects of the invention it may be stated at the outset that the preferred sanding drum construction illustrated herein is adapted to overcome such slackness, and comprises a hollow drum in which a series of duplicate structures for clamping the paper, and a second series, also of duplicate structures, for tensioning the paper are mounted. Each of the clamping and tensioning structures are independently removable from or replaceable in the drum and are arranged therein in alternating relation. The construction of the various parts, as will be presently set forth, lends itself readily to the production of a drum which has a permanent substantially perfect balance.

The clamping structures extend substantially the length of the drum and are arranged for simultaneous actuation by a common means to engage or release both ends of the abrasive sheet, the body of which is wound about the drum. The tensioning structures extend entirely across the length of the drum and are also capable of actuation by a common means to remove them from their tensioning engagement with the paper.

Each of the clamping and tensioning structures, however, are independently held in operative engagement with the paper to pro-

vide, in the case of the clamping structures, a positive clamping action throughout the length of the paper regardless of variations in the thickness thereof, and to insure, in the case of tensioning structures, that each portion of the abrasive sheet throughout the length of the drum will be held under proper tension without respect to irregularities in stretching or unevenness of the felt padding. In addition, the mounting means for incorporating the padding upon the drum includes an adjustment by which slack in the padding may be taken up from time to time as it becomes necessary.

More particularly describing the invention, a drum 10 is indicated which is preferably made of cast iron which may be closed at each end by end plates 10^a secured thereto in any suitable manner. Interiorly of the drum a number of spaced integrally formed transverse webs 11 are provided with centrally positioned supporting bearings 12 for mounting a supporting shaft 13. The drum is rigidly mounted on the shaft in any manner which gives a certain degree of permanence, as by finishing the bearings to provide a driven fit for the shaft.

The drum has a longitudinal gap 14 defined at one side by an edge 15 of the drum body and on the other side by a cast iron structure 16 which is substantially triangular and prismatic in shape. This structure is a removable section of the drum and has an arcuate surface 17 forming a section of the drum periphery and further has an inwardly sloping face 18 which is grooved longitudinally as at 19, near the arcuate surface and also is recessed longitudinally as at 20. Suitable means such as the cap screws 21 entering the webs 11 are provided for securing the section 16 to the drum proper.

The mounting and adjusting means for the padding

The felt sheet 22 which is preferably used in padding the drum is arranged to be secured rigidly at the leading edge of the open seam in the drum and for take-up adjustment at the trailing edge of the drum since in operation any looseness in the padding tends to work its way toward the trailing edge. To this end an elongated screwed cleat or strip 23 engages one end of the padding sheet to clamp the padding between the cleat and the bottom of the groove 19 formed near the arcuate surface of the removable section.

The padding is then wound about the drum and enters the seam therein at the trailing edge 15. This end of the padding is secured between a pair of elongated bars 24 (Fig. 5) as by means of the screws 25, the bars in turn being mounted for movement as a unit toward and from the seam by means of screw threaded engagements with properly formed

portions of the internal webs. For convenience in manufacture and assembly, this screw threaded engagement comprises elongated screws 26 passing through the bars 24 into engagement with bushings 27 mounted in apertures 28 in the several webs.

Set screws 29 are provided at spaced intervals along the bars preferably at points adjacent the adjusting screws 26 to bear against the webs thereby insuring rigidity of the assembly. By this construction the padding layer may be easily mounted, on the drum and adjustment to take up the slack is effected by first loosening the set screws 29 and then tightening the elongated screws 26 to draw the padding to proper tension, after which the set screws may again be brought into engagement with the webs.

The paper clamping and tensioning means in the present embodiment are arranged to be disposed longitudinally of the shaft 13 in such manner as to permit limited swinging motion relative to the shaft to perform their respective functions. As has been mentioned each means comprises a series of similar structures, the number of which depends upon the length of the drum, mounted in alternating relation; that is, a single structure of one series is positioned on the shaft between two structures of the other series. Inasmuch as the structures of each series are substantially the same, only one of each will be described in detail.

The paper clamping means

Referring to Figs. 1, 2 and especially Fig. 3, the clamping member comprises a structure substantially in the form of an arm 30, mounted on the shaft 13 and carrying a clamping head 31 swingable to and from the recess 20 of the removable section 16 to grip the ends of the sheet of paper between the removable structure and the head. In this embodiment the clamping structure is cast in two sections which for convenience will be termed the upper or head section 32 and the lower or counter-balancing section 33.

Each of the sections is formed to provide complementary semi-circular hub portions adapted to receive the shaft 13 relatively snugly therebetween. Lugs 34 formed integrally with the sections adjacent the abutting sides of the semi-circular sections are adapted to receive screws 35 for securing the two sections together with the shaft therebetween. This construction permits the clamping members to be assembled on or removed from the shaft after the shaft and drum are rigidly united.

The arm 30 extending from the hub portion spaces the clamping head an appropriate distance from the hub, the head being substantially elongated and extending longitudinal of the drum. If desired the engaging face

on the head may be knurled to form a more positive paper engaging surface.

The clamping head is preferably spring pressed toward its clamping engagement with the removable drum section 16 and, in the present embodiment, this end is attained by forming a boss 36 integral with one of the lugs 34 on the upper section, as upon the left hand lug in Fig. 3. A closed bore 37 having its axis extending substantially parallel to the arm 30 is formed in the boss to provide a seat for a relatively stiff helical spring 38 which at its free end carries a flat headed pin 39 having its stem fitting into the spring.

Each of the transverse webs of the drum is provided with aligned apertures which receive and form bearings for a clamping cam shaft 40 which runs the full length of the drum and is positioned substantially adjacent the flat heads of the pins 39. At points adjacent these flat heads, cam surfaces are formed on the shaft by flattening the shaft substantially to a semi-circular cross section as shown at 41. The cam shaft 40 has a squared end 42 (Fig. 2) to which a wrench or other suitable tool may be applied for turning the shaft to move the flattened portions of the cam shaft into and out of engagement with the series of pins 39. Thus when the cam shaft 40 is turned with the rounded surfaces of the shaft bearing against the pins 39 the springs 38 will be simultaneously tensioned to swing the series of clamping members 30 about the shaft thereby moving the clamping heads 31 into close abutment with the recess 20 in the removable drum section 16.

Contrarily when the shaft is rotated to oppose the flattened surfaces 41 to the pins, the tension of the springs 38 is relieved and the clamping heads may be swung away from the recess 20 to release the paper.

In forming the recess 20 in the removable section, it will be seen (Fig. 3) that the edge of the removable section is cut away thereby forming, with the web when assembled, shoulders 42 on each of the webs which serve to locate the position of the paper as it is applied to the drum.

In the operation of mounting the abrasive sheet 43 on the drum, the cam shaft 40 is turned to relieve the holding tension of the springs 38 after which the clamping heads may be swung out of engagement to permit removal of the old and worn paper from the drum. A fresh sheet of paper is then wound about the drum starting at the leading edge of the drum with the edge of the paper abutting the stop shoulders 42. The trailing edge of the paper crosses or spans the open seam between the section 16 and the drum edge 15 and is brought into juxtaposition with the leading edge of the paper between the section 16 and the clamping heads 31. Rotation of the cam shaft to tension the springs swings the clamping heads simultaneously to clamp the

two ends of the paper between the heads and the removable section of the drum.

Counter-balancing weights in the form of lugs 44 and 45 formed integrally with the lower section 33 at points diametrically opposite from the clamping head 31 and the boss 36 insure that each of the structures may be perfectly and individually balanced.

The paper tensioning means

The tensioning means as shown in Figs. 1, 2 and particularly Fig. 4 is also in the form of a swinging arm and is cast in upper and lower sections 46 and 47 corresponding, as far as the two semi-circular hub portions and securing lugs 34^a are concerned, to the construction of the hub portion of the clamping members. Thus each individual tensioning structure may also be removed or replaced about the shaft of the drum without disturbing the rest of the assembly.

The upper section of the tensioning structure carries the arm 48 which preferably is integrally formed on the upper section of the hub and, at its upper end, supports a longitudinally extending tensioning blade 49 positioned to engage the abrasive sheet at an appropriate point intermediate the trailing edge of the drum and the clamping head 31. Moreover, the arrangement is such that, in the swinging movement of the tensioning structure about the shaft in one direction, the blade is arranged to exert a pulling force away from the edge of the drum and substantially tangential thereto.

A suitable means for producing the tensioning force comprises, as shown in Fig. 4, a helically coiled spring 50 bearing between the side of the arm 48 corresponding to the trailing edge of the drum and a lug 51 formed integrally on the inner surface of the drum. Guide pins 52 on the arm and lug, about which the spring is seated, maintain the spring in operative relation with respect to the arm and lug. A tensioning cam shaft 54 which may be similar in form and construction to the clamping cam shaft 42 is rotatably mounted in the webs to extend the full length of the drum adjacent to the sides of the series of arms 48 opposite the spring 50 mounting.

The tensioning cam shaft has flattened surfaces 55 movable, upon rotation of the shaft, into position opposite the adjacent sides of the arms 48 to free the arms from the arcuate surfaces of the cam shaft and allow the tension of the springs 51 to force the tensioning blades into engagement with the abrasive sheet. This, in the operation of the drum, is the normal position of the shaft, thus permitting the tensioning blades to be constantly urged in the paper tightening direction. Rotation of the shaft brings the arcuate surfaces thereof into engagement with the sides of the arms

to swing the arms to their remote position, as indicated in Fig. 4, against the tension of the springs 50 and holds the tensioning structures in this position during the removal of an old and insertion of a fresh abrasive sheet.

5 The lower section of each tensioning structure carries a counter-balancing weight 56 disposed substantially diametrically from the arm 48 and plate 49 on the upper section to permit the structures to be individually balanced.

10 It may be seen, from a comparison of the positions of the tensioning blade, as shown in Figs. 2 and 3, that the blade may, when considerable slack has been taken up in the paper, swing past the clamping heads. To permit this, the ends of the clamping heads are spaced apart a sufficient distance to allow the arms 48 of the tensioning structures to pass therebetween. The tensioning blades, 15 however, are preferably of such length that the ends thereof nearly abut, thereby insuring that each portion of the abrasive sheet will be held under tension. It has also been found desirable to form the clamping structures for the extreme ends of the drum as 20 right and left hand members 30° and 30°. These however are substantially the same as the center structures except for the shortening of the head on one side of the arm.

30

Assembly and balancing operation

In assembling the various parts to form a complete operative structure the drum 10 is first secured upon the shaft 13 and the triangular removable section 16 is secured to the drum. This assembly is next mounted for a machining operation, in a well-known manner, and the peripheral surface of the drum 35 is trued or finished to the axis of the shaft.

40 In forming the drum, the webs and other parts formed integrally therewith, are disposed in such manner about the interior of the drum that the drum, shaft and removable section, when assembled, will be nearly balanced. During the finishing operation the balance of the drum about the axis of the shaft may be further corrected to place the assembly substantially in perfect balance.

45 The tensioning and clamping structures are finished and balanced separately by mounting each one individually upon a separate shaft of substantially the same diameter as the shaft 13 and finishing them to a substantially perfect balance about the shaft. Thus when each of the individual structures are secured to the shaft in the drum the resulting structure is true and balanced. An important advantage resulting from the separate balancing of each of the individual structures resides in the fact that any structure in the drum may be removed and replaced by another structure without disturbing or in any way interfering with the balance of the drum.

Operation

Briefly recapitulating the operation of the drum, it is assumed that the abrasive surface is worn out and that the padding layer is 70 slightly loose. To replace the paper, the operator first rotates the tensioning cam shaft 54 to swing the tensioning blades to their remote position and then rotates the clamping cam shaft 40 to release the tension of the clamping springs 38. The paper clamping members may then be pushed to their disengaged position and the worn paper withdrawn from the drum. This exposes the adjusting means for the padding, which may be 75 tightened to a desired tension in the manner previously set forth. A fresh piece of abrasive paper is then placed about the drum in position to be clamped and rotation of the clamping cam shaft swings the clamping heads into engagement with the paper. Subsequently, release of the tensioning means through rotation of the tensioning cam shaft 80 effects a proper tensioning of the paper.

When it becomes necessary or desirable to 85 replace any of the paper clamping or tensioning structures in the drum the operation may be simply and easily performed. The paper and padding strips are first removed from the drum which exposes and permits removal 90 of the triangular drum section 16. Thus a substantially large gap is provided in the drum allowing access to the screws 35 to separate the hub sections and free the desired structures from the shaft. A new and previously balanced structure is then placed 95 properly about the shaft, the screws tightened, the removable section replaced, and the padding and paper strips secured about the drum, after which the drum is again in perfectly balanced condition for use.

100 It will be apparent from the foregoing description that a sanding drum has been provided in which a substantially perfect balance is readily possible, which balance remains true even though replacement of various of the paper working elements may become necessary.

110 I claim as my invention:

1. A sanding drum comprising, in combination, a shaft, a drum mounted rigidly on said shaft having an external surface for presenting an abrasive sheet to a piece of work, a plurality of clamping structures including longitudinally extending clamping heads mounted on said shaft for relative swinging movement into and out of clamping engagement with the sheet, a plurality of tensioning structures including longitudinally extending sheet-engaging tensioning heads mounted alternately on said shaft with respect to said clamping structures and also swingable for engagement with said sheet, said clamping heads being shorter than the tensioning heads to permit swinging movement of said tensioning heads past said clamping heads.

2. A sanding drum having, in combination with a hollow split cylinder mounted for rotation with a shaft, a clamping element for holding an abrasive sheet about the surface of said cylinder, said element comprising an arm mounted on said shaft for rotational movement relative thereto, a clamping head carried by said arm to extend longitudinally of the cylinder adjacent the split portion thereof and movable to and from an abutting engagement with a relatively stationary portion of said cylinder, a boss rigid with said arm and extending substantially at right angles therefrom, a spring seated on said boss, and a shaft having cam surfaces thereon engaged by said spring for compression or release of tension to swing said head into or permit movement thereof away from its clamping position.

3. A sanding drum having, in combination with a hollow split cylinder mounted for rotation with a shaft, a tensioning element for maintaining a clamped abrasive sheet in proper tension comprising an arm mounted on said shaft for relative rotational movement relative thereto, a tensioning head carried by said arm and extending longitudinally of the cylinder near the split therein, a resilient member interposed between said arm and a stationary part of said cylinder normally tending to move said arm and head in a sheet tensioning direction, and a shaft having cam surfaces thereon positioned to engage the opposite side of said arm and upon rotation of said shaft to move said arm against the tension of said resilient member.

4. In a sanding drum, the combination with a split cylinder mounted for rotary movement, of means for holding a padding strip about the external surface of said cylinder and for adjusting the tension thereof comprising a means for securing one end of the padding strip within said cylinder at the leading edge of the split, a pair of bars clamping the other end of said strip therebetween, and means for adjustably securing said bars within said cylinder including screws through said bars engaging portions of said cylinder to draw the bars into the cylinder, and set screws to prevent movement of the bars after adjustment.

5. A sanding drum having, in combination with a hollow split cylinder mounted for rotation with the shaft, a plurality of sheet clamping structures detachably mounted within said drum on said shaft, a plurality of sheet tensioning structures also detachably mounted within said drum on said shaft in alternating relation with said sheet clamping constructions, each of said sheet clamping and sheet tensioning structures having counter-balancing weights formed thereon to permit each structure to be individually balanced about the axis of said shaft.

6. A sanding drum having, in combina-

tion with a hollow split cylinder mounted for rotation with the shaft, a plurality of clamping devices including sheet engaging members mounted on said shaft for swinging movement relative thereto to position said members in or out of clamping engagement with a sheet, a plurality of tensioning structures each including a sheet engaging head also mounted on said shaft for swinging movement to position said heads in or out of engagement with said shaft, said clamping structures and said tensioning structures being disposed along said shaft in alternating relation, said sheet engaging members on the clamping structures being spaced from each other to permit passage of said tensioning structures therebetween in the swinging movement thereof.

In testimony whereof, I have hereunto affixed my signature.

CARL LAWRENCE MATTISON.
